(57) **CLAIM**

The ornamental design for a light fixture, as shown and described.

DESCRIPTION

FIG. 1 is a perspective view of a first embodiment of a light fixture.

FIG. 2 is a view of the front face of the design of FIG. 1.

FIG. 3 is a bottom view of the design of FIG. 1.

FIG. 4 is a back side view of the design of FIG. 1.

FIG. 5 is a top view of the design of FIG. 1.

FIG. 6 is a right side view of the design of FIG. 1.

FIG. 7 is a left side view of the design of FIG. 1.

FIG. 8 is a perspective view of a second embodiment of a light fixture.

FIG. 9 is a view of the front face of the design of FIG. 8.

FIG. 10 is a perspective view of a third embodiment of a light fixture.

FIG. 11 is a view of the front face of the design of FIG. 10.

FIG. 12 is a perspective view of a fourth embodiment of a light fixture.

FIG. 13 is a view of the front face of the design of FIG. 12.

FIG. 14 is a perspective view of a fifth embodiment of a light fixture; and,

FIG. 15 is a view of the front face of the design of FIG. 14. The light fixture has a switch and apertures located along a front face thereof.

The design(s) encompass at least six (apertures) but not necessarily a fixed number of apertures. In other words, there may be more than six apertures for these designs.

The portions shown in dashed lines in the figures form no part of the claimed design. The dot-dash broken line and the dashed broken line immediately adjacent to the shaded surfaces form an unclaimed boundary of the claimed design.
